UNITED STATES PATENT OFFICE.

LANSING ONDERDONK, OF NEW YORK, N. Y., ASSIGNOR TO THE UNION
SPECIAL SEWING MACHINE COMPANY, OF CHICAGO, ILLINOIS.

DESIGN FOR A SEWING-MACHINE FRAME.

SPECIFICATION forming part of Design No. 29,505, dated October 18, 1898.

Application filed April 4, 1898. Serial No. 676,473. Term of patent 14 years.

To all whom it may concern:

Be it known that I, LANSING ONDERDONK, a citizen of the United States, residing at New York, in the county of New York, State of New York, have invented a certain new and original Design for Sewing-Machine Frames, of which the following is a description, reference being had to the accompanying drawings, and to the letters and figures of reference marked thereon.

My invention is a new and original design for a sewing-machine frame; and it consists of the special shape and configuration of the frame as hereinafter described, and shown in the accompanying drawings, in which—

Figure 1 is a side elevation. Fig. 2 is a top plan view of the same, and Fig. 3 is a perspective view of the same.

In the drawings, A represents a standard of the machine, and B the so-called "gooseneck," which is in the shape shown. The base or standard A is enlarged at its lower end, and on its outer edge is curved inwardly a short distance, as shown at 1, and then extends upwardly in practically a straight line to the point 2, where it is narrowed and inclined upwardly, as shown at 3, to the point where the gooseneck begins. The opposite sides 4 of the standard are flattened, as shown. The forward side of the base or standard is at its lower part formed on a convex curve, as

shown at 5, while from said lower part up to the point 6 it is formed on a compound curve. It is provided with a ledge 7 and then extends upward directly parallel with the opposite side, as shown at 8.

C represents the bed-plate or casing of the machine, which is shown as provided with parallel walls 9 10 back to the point 11, where, on the outer side, it is first curved outwardly 40 and then extends on a straight line to the point 12. Then it is curved upwardly and outwardly to the point 13, where it joins the wall 8. On the under side, beginning at the point 11, the lines of the casing are first formed on a concave curve and then straight downward to the point 14 and then inwardly to the point 15, where it joins onto the wall 8. There is also formed between the under side of the casing and the ledge 7 a web 18.

Having thus described my invention, what I claim as new, and desire to secure by Letters Patent, is—

The design for a sewing-machine frame, substantially as shown and described. 55

In testimony whereof I affix my signature in presence of two witnesses.

LANSING ONDERDONK.
